UNITED STATES PATENT OFFICE.

HARRISON H. ROUNTREE, OF CHICAGO, ILLINOIS.

DESIGN FOR A SPROCKET-WHEEL AND CHAIN GUARD.

SPECIFICATION forming part of Design No. 27,071, dated May 18, 1897.

Application filed March 27, 1897. Serial No. 629,625. Term of patent 3½ years.

To all whom it may concern:

Be it known that I, HARRISON H. ROUNTREE, a citizen of the United States, and a resident of Chicago, in the county of Cook and State of Illinois, have invented and produced a new and original Design for Sprocket-Wheel and Driving-Chain Guards or Shields for Bicycles, of which the following is a specification.

In the accompanying drawings, Figure 1 is a perspective view of a guard embodying my design, and Fig. 2 is a transverse section thereof on the line 2 2 of Fig. 1.

The essential features of this design embrace a continuous flanged margin, smooth exteriorly and comprising a straight longitudinal member merging at front into a semi-circular member, the lower part of which is joined to the rear end of the straight member by a member having the form of an ogee curve.

A guard or shield of my design consists of a marginal frame the edges of which are continuous and unbroken and which comprise an upper substantially straight side a , a front

circular side a' , and a lower diagonal side a^2 , having the form of an ogee curve, which extends from the rear end of the side a and merges into the circular side a' at the bottom.

A guard or shield of my design also comprises a flange a^3 , which projects laterally from the edge of the upper and front sides a and a' of the marginal frame, so that it will extend over the driving-chain when said guard or shield is applied to a bicycle.

The space within the marginal frame is occupied by a web of open-work a^4 .

I claim—

The design for a sprocket-wheel and driving-chain guard or shield for bicycles, substantially as herein shown and described.

In testimony that I claim the foregoing as my invention I hereunto set my hand this 20th day of March, 1897, in the presence of two witnesses.

HARRISON H. ROUNTREE.
